(57) **CLAIM**

The ornamental design for a golf club weight, as shown and described.

DESCRIPTION

FIG. 1 is a top, left, and front isometric view of an ornamental design for a golf club weight;

FIG. 2 is a front elevational view of the golf club weight of FIG. 1;

FIG. 3 is a rear elevational view of the golf club weight of FIG. 1;

FIG. 4 is a right side elevational view of the golf club weight of FIG. 1;

FIG. 5 is a left side elevational view of the golf club weight of FIG. 1;

FIG. 6 is a top plan view of the golf club weight of FIG. 1;

FIG. 7 is a bottom plan view of the golf club weight of FIG. 1; and,

FIG. 8 is an isometric view of the golf club weight of FIG. 1 shown in combination with the disclaimed environment of a golf club head.

The dash-dash-dash broken lines illustrate portions of the golf club weight and the environment that form no part of the claimed design. The contrast in shading represents a contrast in appearance only and does not represent any particular color, material, texture, or finish.
